UNITED STATES PATENT OFFICE.

LOUIS W. RICE, OF NEW YORK, N. Y.

DESIGN FOR AN ASH-CUP, MATCH-BOX, AND GLASS-HOLDER.

No. 39,753.

Specification for Design.

Patented Jan. 12, 1909.

Application filed April 8, 1908. Serial No. 425,951. Term of patent 7 years.

To all whom it may concern:

Be it known that I, LOUIS W. RICE, a citizen of the United States of America, residing at New York, in the borough of Manhattan, county and State of New York, have invented a new, original, and ornamental Design for an Ash-Cup, Match-Box, and Glass-Holder, of which the following is a specification, reference being had to the accompanying drawing, forming part thereof.

The Figures 1 and 2 represent respectively a side-elevation and a plan-view of a combined ash-cup, match-box holder and glass holder showing my design.

The design comprises a supporting-plate, an ash-cup at one end of the same with a cigar-rest on the rim thereof, a glass-holder at the opposite end of the plate, and a match-box holder intermediately between the ash-cup and glass-holder.

I claim:

The ornamental design for an ash-cup, match-box and glass-holder, as shown and described.

LOUIS W. RICE.
